UNITED STATES PATENT OFFICE.

WILLIAM REARDON, OF BEACHMONT, MASSACHUSETTS.

SALES-RECORDING DEVICE.

SPECIFICATION forming part of Letters Patent No. 744,937, dated November 24, 1903.

Application filed November 28, 1902. Serial No. 133,003. (No model.)

To all whom it may concern:

Be it known that I, WILLIAM REARDON, a citizen of the United States, residing at Beachmont, in the county of Suffolk and State of Massachusetts, have invented new and useful Improvements in Sales-Recording Devices, of which the following is a specification.

The object of this invention is to provide a cheap, simple, and easily-operated device for simultaneously recording a sale upon a record-slip and upon a check to be given to the customer.

The invention consists in the combination and arrangement of parts set forth in the following specification and particularly pointed out in the claims thereof.

Referring to the drawings, Figure 1 is a plan view of my improved sales-recording device, the stamp being indicated thereon in dotted lines. Fig. 2 is an enlarged transverse section taken on line 2-2 of Fig. 1. Fig. 3 is an enlarged section taken on line 3-3 of Fig. 1. Fig. 4 is a detail front elevation of the locking-strip and lock.

Like numerals refer to like parts throughout the several views of the drawings.

In the drawings, 10 is a base-board, 11 vertical partitions fast to said base-board and extending longitudinally thereof parallel to each other, and 12 are flanges fast to or integral with said partitions and extending partly across the space between said partitions.

13 are locking-plates extending transversely across the top of said partitions, one at each end thereof, each of said locking-plates being provided with a plate 14, pivotally hinged thereto at 15 and provided with a slot 16 to engage a staple 17, said staples being fast to said base-board 10 and each provided with a padlock 18. The locking-plates 13 are provided with holes 19, extending vertically therethrough and engaging locking-pins 20, fast to the base-board 10.

The locking-plates 13 are pivotally hinged at 21 to plates 22, fast to the base-board 10.

Record-slips 23 are placed between the partitions 11, holes being provided in said record-slips to allow them to be slipped over the pins 20. Each of the record-slips contains at one end thereof the number of a waiter or

salesman, as "1," "2," "3," "4," "5," "6," "7," to "14," Fig. 1. The number of the record-slip is also placed on each slip, as well as the waiter's number, these numbers being 55 preferably placed adjacent to the waiter's number upon the slips, as shown in Fig. 1. The numbers of the record-slips may extend from "1" to any desired number.

The stamp by which the amount of the sale 60 is printed simultaneously upon the record-slip and upon the customer's slip is illustrated in side elevation in Fig. 2 and in dotted lines in plan in Fig. 1. The stamp 24 consists of a handle 25 and a holder 26, said 65 holder being provided with a recess 27, extending across one of the flanges 12 and provided, preferably, with a piece of rubber 28 upon each side of said recess, said pieces of rubber having duplicate sets of numerals 70 "29" embossed thereon.

In operating my improved device the record-slips 23 are placed in the proper spaces between the vertical partitions 11, the record-slip for waiter No. 1 being placed opposite the 75 numeral "1," stamped upon one of the locking-plates 13. The record-slip for waiter No. 2 is placed in the space between the partitions opposite the numeral "2," stamped upon one of said locking-plates, and so on. 80 In each of the spaces between the partitions I have illustrated sufficient depth between the under side of the flange 12 and the top of the base-board 10 to insert three record-slips, and as the space is of sufficient length to insert two record-slips it is evident that six record-slips may be inserted in each of the spaces between the partitions 11. Said record-slips are placed over the pins 20, and the locking-plates 13 are lowered into position, 90 the upper ends of the pins projecting through holes provided in said locking-plates. The locking-plates are then secured by means of the padlocks 18 and the device is in readiness for use, all of the record-slips being 95 locked thereto, so that it is impossible to remove them without tearing.

In using my improved device one clerk records all the sales, a number of stamps being held in a convenient receptacle, each having 100 two sets of duplicate numerals upon the under face thereof. The customer's check 30,

Figs. 1 and 2, is brought to the checking-clerk, who places one edge of said strip against one edge of one of the flanges 12 adjacent to the record-slip corresponding with the number of 5 the waiter who brings the customer's check to him. He then stamps simultaneously, by means of the stamp 24, the proper amount (in this particular instance forty cents) upon the record-slip and upon the customer's slip 10 and then returns the customer's check to the waiter. When one record-slip has been used, it is removed and the one beneath is used until the three slips in the space have been used up, when new slips are inserted.

15 It is evident that a larger number of slips may be placed in a space by increasing the depth between the flanges and the top of the base-board. In this case the recess 27 in the under side of the stamp-holder 26 would necessarily be made of greater depth.

20 It will readily be seen that in auditing accounts the amount of sales indicated by the record-slips must balance with the amount of sales recorded upon the customers' checks, 25 and also (each waiter being provided with customers' checks having his special number thereon, as in the instance illustrated in Fig. 1 No. 4) the amount sold by each waiter, as indicated upon his record-slip, must balance 30 with the amount indicated upon the different customers' checks handed in to the cashier with his number thereon.

35 The advantages secured by my improved sales-recording device are simplicity of construction, speed in operation, and accuracy in results desired.

Having thus described my invention, what I claim, and desire by Letters Patent to secure, is—

40 1. In a sales-recording device, a record-slip holder comprising a base-board, a series of parallel longitudinal partitions fast to said base-board, a vertical pin at one end of each of the vertical spaces between said partitions, 45 a plate extending transversely of said parti-

tions and engaging said pins, and means to lock said plate to said base-board.

2. In a sales-recording device, a record-slip holder comprising a base-board, a series of parallel longitudinal partitions fast to said base-board, means to lock a record-slip between two of said partitions, a vertical pin at one end of each of said vertical spaces between two of said partitions, a plate extending transversely of said partitions and engaging said pins, and means to lock said plate to said base-board. 50 55

3. In a sales-recording device, a record-slip holder comprising a base-board, a series of parallel longitudinal partitions fast to said base-board, means to lock a record-slip between two of said partitions, each of said partitions having flanges on the top thereof extending partly across the space inclosed between two of said partitions, a vertical pin at one end of each of said vertical spaces between two of said partitions, a plate extending transversely across the top of said partitions and engaging said pins, and means to lock said plate to said base-board. 60 65 70

4. In a sales-recording device, a record-slip holder comprising a base-board, a series of parallel longitudinal partitions fast to said base-board, means to lock a record-slip between two of said partitions, each of said partitions having flanges on the top thereof extending partly across the space inclosed between two of said partitions, a vertical pin located at each end of each of said spaces, between two of said partitions, plates extending transversely across the top of said partitions and engaging said pins, and means to lock said plates to said base-board. 75 80 85

In testimony whereof I have hereunto set my hand in presence of two subscribing witnesses.

WILLIAM REARDON.
